(57) **CLAIM**

May 21, 2002 (JP) 2002-013467

The ornamental design for a menu display for a mobile phone, as shown and described.

(51) LOC (7) Cl. **14-02**

DESCRIPTION

(52) U.S. Cl. **D14/486**

FIG. 1 is a top, front, and right side perspective view of my new design for a menu display for a mobile phone;

(58) Field of Search D14/485-95; D18/24-33;

FIG. 2 is a front elevation view thereof; and,

D19/6; D20/11; D21/324-33; 345/700-26,

FIG. 3 is a rear elevation view thereof.

764-866

The broken line drawing of a mobile phone in all views is for illustrative purposes only and forms no part of the claimed design.
